UNITED STATES PATENT OFFICE

114,969

DESIGN FOR A CLOCK CASE OR SIMILAR ARTICLE

Charles B. Simmons, Bristol, Conn., assignor to
The Sessions Clock Company, Forestville, Conn.,
a corporation of Connecticut

Application April 13, 1939, Serial No. 84,269

Term of patent 3½ years

To all whom it may concern:

Be it known that I, Charles B. Simmons, a citizen of the United States, residing at Bristol, in the county of Hartford and State of Connecticut, have invented a new, original, and ornamental Design for a Clock Case or Similar Article, of which the following is a specification, reference being had to the accompanying drawing, forming part thereof.

Fig. 1 is a front perspective view of a clock case or similar article, showing my new design; and

Fig. 2 is a side or edge view thereof.

The characteristic feature of my design resides in the provision of the case with louver-like ribbings extending across the face of the case and onto its side.

I claim:

The ornamental design for a clock case or similar article, substantially as shown and described.

CHARLES B. SIMMONS.
